(57) **CLAIM**

The ornamental design for a wing nut, as shown and described.

DESCRIPTION

FIG. 1 is a front perspective view of a first embodiment of wing nut according to the present design;
FIG. 2 is a front elevation view thereof;
FIG. 3 is a rear elevation view thereof;
FIG. 4 is a top plan view thereof;
FIG. 5 is a bottom plan view thereof;
FIG. 6 is a left side elevation view thereof;
FIG. 7 is a right side elevation view thereof;
FIG. 8 is rear perspective view thereof;
FIG. 9 is a top perspective view thereof;
FIG. 10 is a front perspective view of a second embodiment of wing nut according to the present design;
FIG. 11 is a front elevation view thereof;
FIG. 12 is a rear elevation view thereof;
FIG. 13 is a top plan view thereof;
FIG. 14 is a bottom plan view thereof;
FIG. 15 is a left side elevation view thereof;
FIG. 16 is a right side elevation view thereof;
FIG. 17 is rear perspective view thereof;
FIG. 18 is a top perspective view thereof;
FIG. 19 is a front perspective view of a third embodiment of wing nut according to the present design;
FIG. 20 is a front elevation view thereof;
FIG. 21 is a rear elevation view thereof;
FIG. 22 is a top plan view thereof;
FIG. 23 is a bottom plan view thereof;
FIG. 24 is a left side elevation view thereof;
FIG. 25 is a right side elevation view thereof;
FIG. 26 is rear perspective view thereof; and,
FIG. 27 is a top perspective view thereof.
